D. T. MUNGER, OF WATERBURY, CONNECTICUT.

Letters Patent No. 71,042, dated November 19, 1867.

IMPROVED MACHINE FOR MAKING BALL-CHAIN.

The Schedule referred to in these Letters Patent and making part of the same.

TO ALL WHOM IT MAY CONCERN:

Be it known that I, D. T. MUNGER, of Waterbury, in the county of New Haven, and State of Connecticut, have invented a new Machine for Making Ball-Chain; and I do hereby declare the following, when taken in connection with the accompanying drawings and the letters of reference marked thereon, to be a full, clear, and exact description of the same, and which said drawings constitute part of this specification, and represent, in—

Figure 1, a front view.

Figure 2, a side view.

Figure 3, a top view.

Figure 4, a vertical central section.

Figure 5, the rivet.

Figure 6, the blank from which the ball is formed.

Figure 7, the partial formation of the ball.

Figure 8, the chain complete; and in

Figure 9, a vertical section of the same.

This invention relates to an improvement in the manufacture of what is termed ball-chain, that is to say, a chain formed from hollow balls, the several balls being united so as to form a flexible chain.

Heretofore this kind of chain has been formed by passing a link through each ball, and uniting the several links. This necessitates a sufficient distance between the balls to permit the union of the link, and is a comparatively expensive operation. By my invention the cost of the chain is very much reduced, and its appearance very much improved, inasmuch as the link is dispensed with, and the balls lie in close proximity to each other; and consists, first, in swaging the balls so as to close around the neck of a double-headed rivet, then a second ball around the same rivet, and so on successive balls around a separate rivet between each two balls; and second, a mechanism by which the chain is thus constructed.

To enable others to construct my improvement, I will proceed to describe the same as illustrated in the accompanying drawings.

A piece of metal of the proper size, as in fig. 6, is bent in cylindrical form, as in fig. 7, and the two edges united. I prefer to use corrugated metal, but this is not essential. Fig. 5 is a double-headed rivet, formed in machines formed for the purpose. Then the cylinder in fig. 7 is placed in proper dies; or otherwise, and its two ends contracted so as to close around the neck of the rivet, as seen in fig. 9. Then a second ball is in like manner closed around the neck of one of the rivets, and another rivet placed in the neck of the second ball to receive the third, and so on, leaving sufficient play around the rivet to render the chain flexible; and thus the balls are attached together in close proximity to each other, and without the employment of the links heretofore used, and which detract very greatly from the tasteful appearance of the chain.

I will now proceed to describe the machine by which I thus construct the chain.

A is the bed, B the frame which supports the mechanism, C a slide, arranged in guides, *c*, so as to be moved freely up and down by a lever, D, pivoted in the frame at *d*, and so as to move from the position in black to that in red, as denoted in fig. 2, and *vice versa*. Upon the upper end of the slide C is arranged a concave die, E, the concavity corresponding to one-half of the ball of the chain to be produced; and centrally from the bottom of the said die a hole is made, to receive a rivet, as denoted in fig. 4, and so that one head of the rivet will extend up into the die. Above the die E, in proper guides, *f*, are arranged slides, F, each carrying in its inner end a die, and the two dies combined correspond to the other half of the ball, as denoted in fig. 4, and when the three dies, E and F F, are in the position as in fig. 4, they together conform to the shape of the ball to be produced. In the centre of the two dies F and F a perforation is made, so as to encircle the rivet, as seen in fig. 4. The two dies F and F are moved by their respective levers, G G, hung upon a common fulcrum, H, and above the two dies is arranged a plate, I, through which a perforation is formed centrally with the dies, but smaller than the dies, so as to support the last ball made while the next ball is being formed and attached, as seen in fig. 4.

The operation of the machine is as follows: When the die E stands in the position denoted in red, fig. 2, insert the rivet therein, as seen in fig. 4; then place the blank shown in fig. 7 into the die and close the two

dies F, as denoted in red, fig. 3, and in fig. 4; then raise the die E, and the form of the combined dies will contract the blank and close one end around the rivet setting in the bottom of the die, as seen in fig. 4; then open the dies, remove the ball and the rivet, which is securely attached thereto; then place a second rivet and a second blank in the dies in like manner, setting the first ball through the plate I, so that the rivet in the first ball will hang down through the upper dies, as seen in fig. 4; then close the dies as before, and the two ends of the blank are closed, the one upon the upper, and the other upon the lower rivet, and so continuing, adding ball after ball, until the chain is of the length desired. Thus the chain is produced in a very rapid manner, perfect in all its parts and connections, and neat and tasteful in its appearance. I have represented the several dies as moved by their respective levers, and this I find to be the most convenient arrangement, but am not confined to this precise arrangement for operating the dies.

Having thus fully described my invention, what I claim as new and useful, and desire to secure by Letters Patent, is—

1. The die E, combined with the dies F F, so as to operate to close the ball upon the rivets, substantially as herein set forth.
2. The arrangement of the plate I, in combination with the dies E and F F, as and for the purpose specified.

D. T. MUNGER.
